United States Patent Office

Des. 224,732
Patented Sept. 12, 1972

224,732

BOTTLE

James C. McKinney and William D. West, Greenville,
S.C., assignors to Morton-Norwich Products, Inc.

Filed May 3, 1971, Ser. No. 140,002

Term of patent 14 years

Int. Cl. D9—01

U.S. Cl. D9—40

FIG. 1

FIG. 2

FIG. 3

FIG. 4

FIG. 5

FIG. 6

FIG. 7

FIG. 1 is a perspective view of a bottle showing our new design;

FIG. 2 is a top plan view;

FIG. 3 is an elevational view;

FIG. 4 is an elevational view showing the side opposite that seen in FIG. 3;

FIG. 5 is an elevational view looking from the left of FIG. 3;

FIG. 6 is an elevational view looking from the right of FIG. 3; and

FIG. 7 is a frontal view looking from right of FIG. 3 thereof.

We claim:

The ornamental design for a bottle, as shown.
